Letters Patent No. 2299. Dated May 1, 1866.

Design for a Trade Mark.

The schedule referred to in these Letters Patent and making part of the same.

to all whom it may concern:

Be it known that we, Franklin O. Day and
William J. Stewart, of the City and County of St. Louis and State of Missouri,
have invented a new design for a Trade Mark, it being a Brand for Glass
Beer Barrels and we do hereby declare that the following is a full and
exact description thereof, reference being had to the accompanying draw-
ings which fully explain the nature of the invention. On a barrel
of a yellow color, one and one half inches wide, more or less, is painted on
the head of the barrel just inside of the chime and concentric thereto
a field. The field of the barrel is divided by the yellow
row band is to be painted a white color, and on this white color
will the following words are painted in black letters. On the upper
part of the head the words "Derby Frost Day" and on the lower half
of the same the word "Stewart" is painted in capital letters in a cir-
cular line concentric with the chime. The word "Stewart" is painted
in a set capital letters across the center of the band, in a
line, and above it the word "Ginottle" is set in a line, in a line and capi-

2nd Letters but slightly smaller than the following is intended "Type".
Please note and "fix" the following letters and make them identical with
those, viz. "Lindens, Mo."

Having described our invention what we claim and
desire to secure by letter patent is the design for a "Header-Block", the
boxed part arranged substantially as shown and described.
